United States Patent Office

Des. 220,359
Patented Mar. 30, 1971

220,359

CANISTER

Joan G. Stevens, New York, N.Y., assignor to Pantry Queen Products Inc., Brooklyn, N.Y.

Filed Apr. 14, 1970, Ser. No. 22,422

Term of patent 14 years

Int. Cl. D7—01

U.S. CL. D44—6

FIG. 1.

FIG. 2.

FIG. 3.

FIG. 4.

FIG. 1 is a front perspective view of a canister showing my new design;

FIG. 2 is a top plan view thereof;

FIG. 3 is an elevational rear view thereof; and

FIG. 4 is a developed plan view of the ornamentation.

I claim:

The ornamental design for a canister, substantially as shown.
